GEORGE PRIFOILD, OF SOMERVILLE, NEW JERSEY.

METHOD AND APPARATUS FOR PRINTING RUGS.

Application filed December 1, 1926. Serial No. 151,849.

This invention relates to improved methods and apparatus for printing rugs, and particularly rugs made from floor covering in strip form.

- 5 The object of the invention is to print more complicated and attractive designs than have heretofore been used in such rugs, without increasing the size of the printing machine used.
- 10 In making rugs from floor covering made in the strip, such as oil cloth, linoleum and the like, it is customary to pass a continuous strip of the material through a block printing machine containing printing blocks which are supplied with paints of different colors and are timed so as to print on successive zones of the strip to produce the required design. The strip is thereafter cut into rugs.
- 15 As such rugs are ordinarily provided with borders, including end borders extending across the strip and side borders extending along the edges of the strip, two sorts of printing blocks are provided. These include 20 end-border blocks, of which one or two are provided for each color used in the end borders, and side-border-and-field blocks which print sections both of the side borders and of the middle portions or fields of the 25 rugs. Since the side borders of each rug usually correspond with its end borders, one side-border-and-field block is provided for each of the colors used in the end borders. When a considerable number of colors are 30 used, it is impractical to provide additional blocks, and, for this reason, it is necessary to print the middle portion of each rug with the same colors as those which are used in its border. This constitutes a 35 serious limitation which materially detracts from the beauty of such rugs, since correct principles of design require the use in the borders of colors different from, and usually more striking than, those used in the middle 40 part of the rug.

45 By means of the present invention, I am able to produce rugs having their fields and borders printed in different colors without increasing the number of printing blocks 50 which must be used, and consequently without increasing the size of the printing machine used. In this way, I have for the first time made it possible, as a practical matter, to print rugs with correct and at-

tractive designs requiring the use of different colors in the fields of the rugs from those used in their borders. 55

In order that the invention may be clearly understood, I will describe methods of applying it to the printing of two simple rug designs using only a few colors. These illustrations will serve to indicate to those skilled in the art the manner in which the invention may be applied in printing rug designs using a large number of colors. I will describe 60 also a block printing machine embodying the invention, and adapted to aid in carrying out these specific methods. In such descriptions, I shall refer to the accompanying drawings, in which:—

70 Fig. 1 illustrates a rug design printed by means of the invention:

Figs. 2, 3, 4, 5, 6 and 7 are inverted plan views of the printing blocks used in printing the design shown in Fig. 1;

75 Fig. 8 shows another rug design printed in accordance with the invention;

Figs. 9, 10, 11, 12, 13 and 14 are inverted plan views of the printing blocks used in printing the design shown in Fig. 8; and

80 Fig. 15 is a plan view of a conventional block printing machine modified in accordance with the invention for printing the designs shown in Figs. 1 and 8.

85 The rug shown in Fig. 1 has a border containing two colors and a field containing two different colors. It is printed from only six blocks. There are four end-border blocks of which two, 1, 2, are used in printing the left-end border of each rug, and the other two, 90 3, 4 in printing the right-end borders. The block 1 has raised portions providing spaced figures 1^a, 1^b, 1^c. The block 2 has a raised portion providing a single figure 2^a adapted to register with the figures 1^a, 1^b, 1^c. The blocks 3, 4, have figures 3^a, 4^a, 4^b, 4^c, corresponding to those of the blocks 1, 2. There are two side-border-and-field blocks 5, 6. The block 5 is provided with side-border figures 95 5^a, 5^b, 5^c, similar to the end-border figures 1^a, 1^b, 1^c, and also with field figures 5^d which are spaced inward from the side-border figures. The block 6 is provided with side-border figures 6^a similar to the end-border figure 2^a and adapted to register with the 100 side-border figures 5^a, 5^b, 5^c, and also a field figure 6^b, which is spaced from the side-border figures 6^a and is adapted to register 105

with the field figures 5^a. It should be noted that the spaces 5^x which separate the side-border figures and the field figure of the block 5 are located at a different distance from the center of the block than are the spaces 6^x which separate the side-border figures and field figure of the block 6.

In printing the rug design shown in Fig. 1, different colored paints are supplied to the two left-end border blocks 1 and 2, and registering impressions of these blocks are made in spaced zones of the strip of floor covering, for example, in the zone A shown in Fig. 1. The right-end border blocks 3 and 4 are supplied with paints of the same two colors as the blocks 1 and 2, and registering impressions are made from these blocks in spaced zones, for example, in the zone G shown in Fig. 1. The outer-end portions of the blocks 5 and 6 containing the side-border figures 5^a, 5^b, 5^c, and 6^a are supplied with paints of the same two colors as those supplied to the blocks 1 and 2 and the blocks 3 and 4. Paints of two different, and preferably paler, colors are supplied to the middle portions of the blocks 5 and 6 containing the figures 5^d and 6^b. Registering impressions of the blocks 5 and 6 are made on each of the zones between the zones on which the end-border blocks are impressed, for example, on each of the zones B, C, D, E and F of Fig. 1. The fact that the middle figures of the blocks 5 and 6 are spaced from the end figures thereof prevents any mixing of the colors supplied to the end and middle figures of each block. The spacing of the figures, however, causes no blank spaces in the rug, owing to the fact that the figures 5^b of the block 5 cover the spaces 6^x in the impression of the block 6, while the end portions of the figure 6^b of the block 6 cover the spaces 5^x of the impressions of the block 5. The result is to produce a bordered rug having its entire surface covered with paint and having a field containing different colors from those used in its border.

The rug shown in Fig. 8 has a border of one color, end-border figures and a center figure of another color, and field figures of a third color. This rug may best be printed by a method embodying not only the present invention but also the invention described in my co-pending application, Serial No. 124,572, filed July 24, 1926.

Only six blocks are required to print this rug. The block 7 has two raised figures 7^a, which are spaced from the center of the block, and also from its outer edge. The block 8 has two side-border figures 8^a and a central figure 8^b spaced from the side-border figures, and adapted to form both an end-border figure and a center figure in the rug. The block 9 has two side-border figures 9^a similar to the side-border figures 8^a, and field figures 9^b spaced inwardly from the side-

border figures. The block 10 has figures 10^a adapted to fill in the spaces left by registering impressions of the figures of the blocks 7 and 8. The block 11 has a raised figure 11^a adapted to register with the figures 9^a and 9^b of the block 9. The block 12 has a figure 12^a adapted to register with the figures 8^a and 8^b of the block 8. 70

In printing the rug shown in Fig. 8 from the blocks which have been described, the middle portion of the block 8 and end portions thereof are supplied with paints of different colors. The block 7 is supplied with paint of the same color as that supplied to the end portions of the block 8. The block 10 is supplied with paint of a color suitable for a background, such as white or grey. Registering impressions of the blocks 7, 8 and 10 are made in each fourth zone of the strip, for example, the zones A' and AA' 85 shown in Fig. 8. The impressions from these three blocks completely cover the surfaces of these zones.

Another impression of the block 8 is made on the zones midway between those in which the three blocks are impressed, for example, on the zone C' shown in Fig. 8. An impression of the block 12, supplied with the same background color as the block 10, is made in register with the impression of the block 8 90 upon the zone C'. These two impressions completely cover the surface of this zone.

The end portions of the block 9 are supplied with paint of the same color as that supplied to the end portions of the block 8, 100 while the middle portion of the block 9 is supplied with another color not used elsewhere. Registering impressions of the block 9 and the block 11, which is supplied with the same background color as the blocks 10 105 and 12, are made on alternate zones of the strip, for example, on the zones B' and D' of Fig. 8.

It will be noted that the background blocks 11 and 12 fill in the spaces between the differently colored figures in the impressions of the blocks 9 and 10 on the zones B', C' and D', while the background block 10 and the end-border block 7 fill in the spaces between the differently colored figures in the impressions of the block 8 upon the zones A' and AA'. The result is that the surface of the rug is completely covered with paint, while the rug design having a border of one color, end-border figures and a center figure of another color, and field figures of a third color has been printed with the use of only three blocks, in addition to the background blocks. 110

The two specific methods which have been described may be carried out by means of the block printing machine shown in Fig. 15.

This machine has the usual frame 20 carrying a long table 21 for supporting the strip of floor covering to be printed. Belts 22 extending along the side edges of the 115 120 125

table, and provided with pins to engage the strip, pass around pairs of pulleys 23, 24, one of which is intermittently driven, so that the belts cause a step-by-step longitudinal movement of the strip. The block carriers X^1 — X^6 are of usual construction, each being provided with a cross beam 25 above the table, and with side members 26 which are slidably mounted on the frame, so that the block carriers may be raised and lowered by means of cams 27. With each carrier is associated a latch 28 for holding it out of operation, and each latch is provided with control mechanism 29, such as that described in my Patent No. 1,145,794, which may be set so as to hold the carrier with which the latch co-operates out of operation for any desired length of time. Paint carriages Y^1 — Y^6 are mounted for reciprocatory movement in directions longitudinal of the table top and strip. The usual moving means 31, 32 are provided for causing such reciprocatory movement of the carriages, while the blocks are in their raised position. Each carriage is provided with a trough 30 extending across the table top, and in each trough is journaled a shaft 33. On the shafts 33 of the carriages Y^1 , Y^2 , Y^5 , Y^6 are mounted rollers 34, which extend substantially the whole length of the troughs of these carriages, dip in the paint in the carriages, and serve to apply it to one of the blocks when the carriage is passed under the block. On the shaft 33 of the carriage Y^3 is mounted a longitudinally divided roller 35 consisting of three spaced sections 35^a, 35^b, 35^c. A similar divided roller 36 is mounted on the shaft of the carriage Y^4 . The troughs 30 of the carriages Y^3 and Y^4 are each divided into three parts by partitions 37, 38 positioned at the division points of the divided rollers. Each partition contains a recess in its upper edge to permit passage of the shaft 33. The partitions 37 are out of line with the partitions 38, so that the end parts of the middle portion 35^b of the divided roller 35 are directly in front of the partitions 38, while the outer portions 36^a, 36^c of the divided roller 36 are directly behind the partitions 37. It will be noted that the partitions 38 correspond in position with the spaces 5^x of the block 5 shown in Fig. 6, while the partitions 37 correspond with the spaces 6^x of the block 6 shown in Fig. 7.

In using the machine described to print the rug design shown in Fig. 1, the blocks 1, 2 are secured to the block carriers X^1 , X^2 , the blocks 3, 4 to the carriers X^5 , X^6 , and the blocks 5, 6 to the carriers X^3 , X^4 . The troughs of the carriages Y^1 , Y^5 , and the outer portions of the trough of the carriage Y^3 are filled with paint of one of the colors to be used in the border, while the paint of the other border color is placed in the troughs of the carriages Y^2 , Y^6 , and the end

portions of the trough of the carriage Y^4 . Paints of the two colors to be used in the field of the rug are placed in the middle portions of the carriages Y^3 , Y^4 . The regulating mechanisms 29 are then adjusted so as to cause the blocks 1 and 2 (on the carriers X^1 , X^2), and 3 and 4 (on the carriers X^5 , X^6) to make registering impressions on spaced zones of the strip, and to cause the blocks 5 and 6 (on the carriers X^3 , X^4) to make registering impressions on the remaining zones of the strip. It will be readily understood that when the machine is so arranged and adjusted, it is adapted automatically to carry out the first specific method described, and to print the rug design shown in Fig. 1.

In using the machine to print the rug design shown in Fig. 8, the blocks 7, 10, 9, 8, 11 and 12 may be secured to the block carriers X^1 — X^6 in the order stated. Paint of the color to be used in the border is then placed in the end portions of the troughs of the carriages Y^3 and Y^4 , and in the trough of the carriage Y^1 . Paint of the color to be used for the end-border figure and the center figure is placed in the central portion of the trough of the carriage Y^4 , while paint of the color to be used for the field figures is placed in the central portion of the trough of the carriage Y^3 . White paint is placed in the troughs of the carriages Y^2 , Y^5 and Y^6 . The control mechanisms 29 are then adjusted to cause the blocks 8, 9 and 11 (on the carriers X^4 , X^3 , X^5) to print on alternate zones of the strip, and the blocks 7, 11 and 12 (on the carriers X^1 , X^5 , X^6) to print on each fourth zone of the strip, the timing being such as to produce the proper registering, hereinbefore described. It is apparent that when the machine is so arranged, it is adapted automatically to carry out the second specific method described, and to print the rug design shown in Fig. 8.

I wish it clearly understood that the invention is by no means limited to the specific methods and machine, which have been described in detail merely for the purpose of illustrating the carrying out of the invention.

What I claim is:

1. The method of printing bordered rug designs on a strip of floor covering, which comprises applying a color across spaced zones of the strip to form end borders, applying the same color and another color in spaced positions across an intermediate zone of the strip at a single impression to form side borders and field figures, and applying a color to the spaces between said side borders and field figures at another impression.

2. The method of printing designs on a longitudinally moved strip, which comprises the simultaneous application of different colors in spaced positions across the strip

while the strip is in one position, and the application of a color to the space between said different colors when the strip is in another position.

3. The method of printing designs on a longitudinally moved strip, which comprises the simultaneous application of different colors in more than two spaced positions across the strip while the strip is in one position, and the application of other different colors to the spaces between the first different colors when the strip is in another position.

4. The improvement in the art of printing bordered rug designs on a strip of floor covering in a block printing machine, which consists in utilizing the middle portions of the side-border blocks to print a field of colors different from those of the side border, by supplying to the middle portions of such blocks printing media of colors different from those supplied to their end portions.

5. The improvement in the art of printing bordered rug designs on a strip of floor covering in a block printing machine, which consists in utilizing the middle portion of a side-border block to print a field of a color different from that of the side border, by forming on said block figures spaced inward from its side-border figures, supplying to the middle portion of the block containing such figures a printing medium of a color different from that supplied to the side-border figures of the block, making an impression from said block, and filling the spaces between the impressions of the field figures and

side-border figures by the impression of another block.

6. In a block printing machine having means for feeding a strip longitudinally and intermittently, and a series of block printing units extending across the strip, the combination of a unit having a block with spaced raised printing surfaces at different distances from the center line of the strip and means for supplying different printing media to said printing surfaces, another unit having a block with raised printing surfaces positioned in line with the spaces between the printing surfaces of the first block and means for supplying printing medium to said printing surface, and timing means to cause said units to operate successively on the same zones of the strip.

7. A block printing machine, as described in claim 6, in which the printing media supplying means of the first unit comprises a transverse trough containing partitions in line with the spaces between the printing surfaces of the block of this unit and a roller in the trough having its surface interrupted at said partitions.

8. A block printing machine, as described in claim 6, in which the printing media supplying means of each of the two units comprises a trough having partitions therein and a divided roller in said trough, the partitions in one trough being out of line with those in the other.

In testimony whereof I have hereunto set my hand.

GEORGE PRIFOLD.
